INVENTOR.

UNITED STATES PATENT OFFICE.

HOMAS SANDERS, OF KINGMAN, INDIANA.

TROLLEY-WHEEL MOUNT.

1,142,846.

Specification of Letters Patent. Patented June 15, 1915.

Application filed February 6, 1915. Serial No. 6,581.

To all whom it may concern:

Be it known that I, THOMAS SANDERS, a citizen of the United States, residing at Kingman, in the county of Fountain, Indiana, have invented a new and useful Improvement in Trolley-Wheel Mounts, of which the following is a specification.

My invention relates to that class of trolley-wheel mounts, wherein a substantial mount is provided whereby a trolley-wheel is supported in bearings, and upon the extreme end of a trolley-pole, and the objects of the invention are: first, to provide a suitable bearing and support for a trolley-wheel upon the extreme end of a trolley-pole; second, to provide such a trolley-wheel mount, which by reason of its peculiar structure and attachments, permits an automatic adjustment in the position of the trolley-wheel while traversing a curve, for the purpose of avoiding the danger of the trolley-wheel "jumping" the wire; and third to provide such a trolley-wheel mount, which will be substantial, sightly and safe against displacement. These objects I attain by means of the mechanism illustrated in the accompanying drawings, in which:—

Figure 1, is a side view of the trolley-wheel and mount. Fig. 2, is a vertical sectional view of the mount. Fig. 3, is a front view of the trolley-wheel and its mount.

Similar letters of reference refer to similar parts throughout the several views.

The letter *a* indicates a trolley-wheel, of the usual shive-wheel type, provided with a hollow hub *b*, supported rotatably upon a shaft *c*. The hub *b* is perforated to form an oil-vent *d*, said oil-vent extending from the outer side of the hub in a diagonal direction downward toward the center of the shaft *c*, and for the purpose of lubricating the said shaft.

The letter *A* indicates a trolley-wheel mount, which consists of a trolley-head *e* and a head-stock *f*.

The trolley-head *e* consists of a U-shaped, or fork-like member, composed of a solid base *g* and two parallel, upwardly projecting bearing-arms *h*.

The bearing-arms *h* are perforated at their upper ends, said perforations being disposed opposite one to the other, and forming journal-bearings *i*, wherein the extreme ends of the shaft *c* are journaled, respectively.

The base *g* of the trolley-head is perfo-

rated vertically and centrally to admit the hereinafter described journal-pin *j*, upon which the trolley rotates. The extreme ends of the shaft *c* are journaled in the journal-bearings *i* and said shaft supports the trolley-wheel *a*. The extreme ends of the shaft *c* project beyond the journal-bearings *i*, and are perforated to receive the cotter-pins *m*, respectively, whereby said shaft is prevented from lateral movement. The trolley-head is flat upon either side, for the purpose of presenting a flat bearing surface to two retaining springs *s*, hereinafter described.

The head stock *f* consists of a metallic, cone-shaped member, flattened upon two opposite sides, and inverted to place the larger end upward. The central portion of the head-stock *f* is perforated horizontally by a large slot *t*, for the purpose of reducing the weight of the stock, and to permit the placement of the journal-pin *j*. The upper portion of the stock *f* is provided with a perpendicular and centrally located, internally-threaded perforation *n*, adapted to receive the journal-pin *j*, as shown. The journal-pin *j* is provided with external threads *u*, throughout its lower portion, adapted to screw into the threaded perforation *n* of the head-stock *f*, and the upper portion is proportioned to nicely fit into the vertical perforation provided therefor in the base of the trolley-head *e*.

The journal-pin *j* is provided with a head *o* upon the lower end, adapted to seat itself firmly against the body of the stock, and is perforated at the upper and projecting end, to receive a cotter-pin *p*, whereby the trolley-head is confined upon said journal-pin. The lower portion of the head-stock *f* is hollow perpendicularly, and adapted to receive the outer end of a trolley-pole *w*, upon which the trolley-mount is supported and firmly attached by means of a pin *v*, which passes through opposite sides of the lower end of the head-stock and the trolley-pole, respectively. A broad, flat spring *s*, wide at the upper end and tapering toward the bottom, is firmly attached by means of screws *q* to either flattened side of the head-stock, and is so positioned that the broad, upper end thereof, will project upward and bear against the flattened sides of the trolley-head, respectively, as shown. The springs *s* are disposed opposite to each other, and are so adjusted that they bear firmly against the corresponding sides of the trolley-head,

thereby serving to hold the trolley-head and its wheels in perfect alinement with the head-stock, and incidentally in perfect alinement with a straight trolley-wire α , against which the trolley-pole holds said wheel.

5 The springs s are designed with proper strength to retain the trolley-head rigidly in alinement with the head-stock, as long as the trolley-wheel follows a straight trolley-wire, but are of sufficient elasticity to respond proportionately to lateral pressure, exerted by the trolley-wire, through the trolley-wheel and trolley-head, while traversing a curve. Thus, by reason of the 10 nicely proportioned pressure exerted by the springs s , the trolley-wheel is at all times held in perfect alinement with the trolley-wire it follows, and all danger is avoided of said wheel "crossing" or "jumping" the 15 wire, and causing broken cross-wire and other troubles incident to such accidents.

10 The advantages claimed for my invention, over similar devices used heretofore, consist in the simple, compact, and substantial structure of the mount; the nicely adjusted flexibility of the trolley-head, attained by reason of the peculiar structure 25 thereof.

What I claim as new and useful, and desire to secure by Letters Patent, is:

1. The combination with a rotatable trolley-head and trolley-wheel axle or shaft, with a head-stock, adapted to movably support said trolley-head, a journal-pin fixed 35 centrally on the body of said head-stock and adapted to confine said trolley-head in movable connection with said head-stock, a pair of oppositely disposed springs attached to said head-stock, and adapted to bear upon 40 opposite sides of said trolley-head, all substantially as described and for the purpose set forth.

2. In a trolley-wheel mount, the combination of a rotatable trolley-head, said trolley-head consisting of a base and two bearing-arms; and journal-bearing in said bearing-arms, adapted to receive a trolley-wheel axle, or shaft, with a head-stock adapted to support said trolley-head upon its upper face, a journal-pin threaded centrally into 45 and projecting upwardly from the upper face of said head-stock, and adapted to confine said trolley-head in movable connection with the head-stock, two opposing springs, mounted upon opposite sides of said head-stock and projecting upwardly, and adapted to press against opposite sides of said trolley-head, and means of attaching said head-stock upon the extreme end of a trolley-pole, all substantially as described and shown, 50 and for the purposes set forth.

3. In a trolley-wheel mount, consisting of a rotatable trolley-head, and a fixed head-stock, in movable connection with each other, means of attaching said members together, 55 a pair of opposing springs, fixed upon the respective sides of said head-stock and adapted to bear against the corresponding sides of said trolley-head, a hollow, lower portion of said head-stock adapted to receive the end of a trolley-pole, means of attaching said head stock to a trolley-pole, and a trolley-wheel shaft journaled in, and supported by, said trolley-head, all substantially 60 as described and shown, and for the purposes set forth.

In testimony that I claim the foregoing as my own, I have affixed my signature hereto, in the presence of two witnesses.

THOMAS SANDERS.
